UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 22,894, dated November 14, 1893.

Application filed October 7, 1893. Serial No. 487,515. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of a series of ornamental scrolls forming panels, with vase-like ornaments in the center of said panels filled with fruit, and sprays of flowers and leaves springing from the sides of said ornaments as represented in the accompanying drawing. The border or upper portion of said design is formed 10 of ornamental scrolls with the vase-like ornaments arranged above the ornamental scrolls and filled with fruit, and festoons of flowers and leaves hanging from the sides of said ornaments and connected with said ornamental scrolls as represented in the drawing. 20

What I claim is—

1. The design for wall paper herein shown and described.

2. In the design for wall paper the border herein shown and described. 25

Witness my hand this 2d day of October, 1893.

CHARLES BOOZE.
